UNITED STATES PATENT OFFICE.

JOSEPH M. EISLER, OF DETROIT, MICHIGAN.

INTERNAL-COMBUSTION ENGINE.

1,371,550.

Specification of Letters Patent. Patented Mar. 15, 1921.

Application filed January 5, 1920. Serial No. 349,357.

To all whom it may concern:

Be it known that I, JOSEPH M. EISLER, a citizen of the United States, residing at Detroit, county of Wayne, State of Michigan, have invented a certain new and useful Improvement in Internal-Combustion Engines, and declare the following to be a full, clear, and exact description of the same, such as will enable others skilled in the art to which it pertains to make and use the same, reference being had to the accompanying drawings, which form a part of this specification.

My invention relates to improvements in internal combustion engines, and particularly to that type in which each end of the cylinder is utilized as an explosion chamber; in improved means of valve operation for such a type of construction; and in improved means for lubricating the piston.

20 In the drawings—

Figure 1 is an elevation, partly in section of a four cylinder type of motor built in accordance with my improved design.

Fig. 2 is a vertical cross section showing 25 the inlet valve open at the bottom of the cylinder.

Fig. 3 is a vertical cross section showing the inlet valve open at the top of the cylinder.

30 Let *a*, represent the engine casing, *b*, the driven crank shaft, *c*, a pitman rod carried by one of its cranks, which pitman rod pivotally carries a cross head *d*, movable within guides *e*—*e* parallel to the bore of the cylinder *f*. A piston *g*, is carried from cross head *d*, by means of a piston rod *h*. Cylinder *f*, is provided in the usual manner with coating chambers *f*¹ and *f*² located in the walls thereof. At each end of the 35 cylinder are valve casings *i*—*i* communicating with the interior thereof in manner shown, so as to provide inlet and exhaust passageways thereto, and provided with valves *j*, adapted to seat in said casing, each held in place by means of a helical valve spring *k*, which encircles the valve stem *m*. The vertical movement of each valve stem is directed by means of a guide *m*², as shown.

40 In Fig. 1 of the drawing the casing is cut 50 away to show method of piston lubrication and valve actuation, and exhaust and intake manifolds are indicated at *p* and *p*² respectively.

The piston *g*, adapted to be driven by an 55 explosion at either end of the cylinder is provided with two sets of piston rings, one

at each end, and is hollowed out as shown for purposes of lubrication. Lubricant is supplied the interior of this piston *g* by means of oil pipe *q*, which enters through the piston rod *h*. This oil conduit after it has extended longitudinally of the piston rod sufficiently to permit the full upward stroke of the piston, is bent in form of a U with parallel arms. The arm *q*², which is 65 complementary to the arm *q*, which forms the oil conduit through the piston rod, is adapted for reciprocatory movement within an oil passageway *r*, coincident with the operation of the piston, which oil passageway *r*, is supplied with lubricant in the usual manner from the oil pump which supplies the remainder of the system. As the oil is forced from the pump, it will be passed through the tube *r*, and the U pipe 70 into the interior of the piston. It will be observed that the arm *q* of the U tube passes longitudinally through the piston rod through a somewhat larger longitudinal passageway *v*, which extends the entire 75 length of the rod, so that the oil which enters through such tube *q*, and does not drain out from the flange *s*, through the exits *s*² may drain back through such passageway *v*, along the exterior wall of the tube *q*, into 80 the engine.

A check valve *w*, is provided so that the oil will flow but one way through such U tube. This is of conventional structure.

Due to the reciprocatory movement of the 90 piston as the oil emerges from the end of the tube *q*, it is thrown against the upper wall of the piston and is splashed back into the circumferential flange *s*, which encircles the interior of the piston, and drains out 95 through the lubricant exits *s*² so as to lubricate the piston head.

It will be observed that but one cam shaft *o*, is provided with eccentric cams *n* and *n*² located side by side thereon, so positioned 100 that valves *j*, will be actuated in proper firing order by means of such cams operating the valve tappets *m*² which in turn actuate the valve stems *m*. Inlet and exhaust valves are offset as shown so as to permit 105 this method of cam arrangement and valve operation. The usual valve spring *k*, is in each instance provided for seating the valve.

What I claim is—

1. In an internal combustion engine a 110 cylinder, a hollow piston adapted to reciprocate in said cylinder, oil ducts leading

through the outer wall of said cylinder, a U shaped lubricant conduit one arm of which extends longitudinally through the piston rod discharging into the interior of said piston, the other arm of which is parallel thereto and is sleeved and adapted for reciprocatory movement within an oil passageway of the oiling system.

2. In an internal combustion engine, a cylinder, a hollow piston adapted to reciprocate therein, a hollow piston rod, a U shaped lubricant conduit one arm of which passes through the interior of the hollow piston rod spaced from the wall of thereof so as to leave an annular passageway between the conduit and the wall of the passageway through the piston rod adapted to permit oil to drain from the interior of the hollow piston through the piston rod, the other arm of such U shaped conduit sleeved for reciprocatory movement within an oil passageway of the oiling system.

3. In an internal combustion engine, a cylinder, a hollow piston adapted to reciprocate therein, such piston provided with a hollow piston rod adapted to permit the flow

of lubricant therethrough from the interior of the piston, a separate oil conduit extending through the interior of said piston rod but spaced from the wall thereof so as to leave an oil passageway exterior the conduit, means for supplying oil through such conduit to the interior of the piston.

4. In an internal combustion engine, a cylinder, a hollow piston adapted to reciprocate therein, such piston provided with a hollow piston rod, a separate oil conduit extending through the interior of the said piston rod but spaced therefrom so as to provide a lubricant passageway extending through such piston rod along the exterior of said inner conduit, such piston provided with an internally projecting flange, the end of said conduit which extends through the hollow piston rod extending sufficiently into the interior of the piston so that oil passing therethrough is thrown against the head of the piston during the operation thereof.

In testimony whereof, I sign this specification.

JOSEPH M. EISLER.
